METHOD OF MAKING BRUSHES

Otto W. Sticht, Orange, N. J.

Application September 12, 1942, Serial No. 458,121

4 Claims. (Cl. 300—21)

This invention relates to brushes and method of making said brushes, and particularly to the securing of a tuft of hair in a tubular holder or ferrule of fibrous material, such as paper spirally wound, extruded or produced in any other suitable manner.

It has been the common practice to mount the tuft of hair in a metal holder or ferrule by inserting one end portion of the tuft of hair into one end portion of the metal ferrule and then crimping said end portion of the metal ferrule upon the end portion of the tuft of hair engaged in the ferrule.

It has been necessary to provide a substitute for the metal ferrule due to the lack of metal for such use, and the most suitable substitute for metal has been found to be fibrous tubing, but said tubing is not adapted to be crimped in the manner of a metal ferrule to retain a tuft of hair therein as the fibrous tubing is not as rigid as the metal ferrule.

It is the principal object of the present invention to adapt paper tubing as a holder for a tuft of hair by providing means to secure the tuft of hair in one end portion of a paper tubing which will have no effect on lacquer or paint and therefore will not cause changes in the shape of the portion of the tuft of hair projecting from the paper tubing, and that solvents, such as acetate, acetone, ether and other similar solvents, have no effect on such securing means.

It is another object of the invention to provide a method of assembling the securing means, the tuft of hair and the paper tubing whereby the securing means will hold the tuft of hair uniformly and firmly in the holder of paper tubing, and the portion of the tuft of hair projecting from the holder may be formed to any shape desired.

Other objects and advantages of the invention will be disclosed in the detailed description of the invention.

In the drawing accompanying and forming a part of this application,

Figure 1 is a perspective view of a length of paper tubing constituting a holder for a tuft of hair.

Figure 2 is a perspective view of the tuft of hair.

Figure 3 is a diagrammatic view showing the application of a thermoplastic to an end portion of the tuft of hair.

Figure 4 is a composite view in perspective of the tuft of hair having the thermoplastic applied to an end portion thereof positioned relative to one end portion of the holder prior to inserting the tuft of hair into the holder.

Figure 5 is a perspective view showing the tuft of hair inserted in the holder in sequence to the condition of the parts shown in Figure 4.

Figure 6 is a fragmentary view of means to apply heat and pressure to the end of the holder engaged by the tuft of hair and the thermoplastic to fuse the thermoplastic and impregnate the tuft of hair and holder therewith and form the projecting portion of the tuft of hair to the shape desired.

Figure 7 is a perspective view of a fully assembled brush subsequent to the heat and pressure applying means.

Figure 8 is a fragmentary plan view of dies forming the heat and pressure applying means of Figure 6 in an inoperative position.

In carrying out the embodiment of the invention illustrated in the accompanying drawing, there is provided a holder comprising a length of fibrous tubing 9, such as paper spirally wound, extruded or produced to tubular form in any other suitable manner. The length of the tubular holder depends on the use of the brush and whether the holder is to form the handle of the brush or constitute means for mounting the bristles of the brush to a handle. The bristles of the brush comprise a tuft of hair 10 adapted to be mounted in the holder 9 by inserting an end portion of the tuft of hair in an end portion of the holder with the opposite end portion of the tuft of hair projecting from the holder, as shown in Figure 5.

The usual method of securing the tuft of hair in the holder is to clamp or crimp the opposite wall portions of the holder together upon the end portion of the tuft of hair engaged in the holder, but this method is not suitable for a holder constructed of fibrous tubing, as said tubing is not of sufficient rigidity to retain its crimped condition and uniformly and firmly hold the tuft of hair.

Therefore, it has been necessary to provide a new method of securing the tuft of hair in the holder, and it has been found that a suitable thermoplastic applied to the end portion of either the holder or tuft of hair before inserting the tuft of hair into the end portion of the holder and the subsequent fusing and compressing of said thermoplastic would uniformly and firmly unite the tuft of hair to the holder.

In carrying out this new method of uniting a tuft of hair to a holder composed of fibrous tubing, it is necessary to provide a thermoplastic which will not affect lacquer or paint and cause changes in the shape of the tuft of hair or bristles of the

brush, and that solvents, such as acetate, acetone, ether or other similar solvents, will have no effect on such thermoplastic, as the holders and tufts of hair are used in finger nail enameling and artist's brushes. It has been found that sulphur meets these requirements and has the desired properties of being readily workable by being fusible and viscous at temperatures below the scorching or burning point of the fibrous tubing.

To facilitate the application of the sulphur to the end portion of either the holder 9 or tuft of hair 10, a vehicle is provided for the sulphur which forms with the sulphur a sulphur mixture and it has been found that alcohol is most suitable for the purpose, as it has a boiling and evaporating point lower than the fusing temperature of sulphur. The mixture of sulphur and alcohol is placed in a suitable receptacle, as shown at 11 in Figure 3, and the end portion of either the holder or tuft of hair is dipped into the sulphur mixture to obtain a deposit of the mixture thereon and the end having said deposit is engaged with the other element of the combination of holder and tuft of hair. In the present illustration of the invention, one end of the tuft of hair 10 is dipped in the mixture of thermoplastic, as shown in Figure 3, to approximately one-half of its length as indicated at 12, and then subsequently, the thermoplastic coated end portion 12 of the tuft of hair is inserted in an end portion of the holder 9, as shown in Figures 4 and 5, with the uncoated end portion of the tuft of hair projecting from the holder, as shown in Figure 5.

It will be obvious that an end portion of the holder 9 could be dipped in the thermoplastic mixture in receptacle 11 to a depth substantially equal to one-half of the length of the tuft of hair, and subsequently, an end portion of the tuft of hair is inserted in the thermoplastic coated end portion of the holder.

After the thermoplastic is interposed between the engaged portions of the holder and tuft of hair by the methods set forth hereinbefore or by any other suitable methods, the end portion of the holder having the tuft of hair engaged therein is subjected to heat and pressure to fuse the thermoplastic and form said end of the holder to any desirable shape depending upon the shape of the bristles or the projecting portion of the tuft of hair desired. If it is desired to have said projecting portion of the tuft of hair of circular form in cross section, the adjacent end of the holder is compressed to circular form, and if it is desired to have the projecting end portion of the tuft of hair of elliptical or flat form in cross section, the opposite wall portions of the adjacent end portion of the holder are pressed together to flatten said end portion of the holder.

In the present illustration of the invention, the projecting end portion of the tuft of hair is shaped to elliptical form and this is accomplished by a pair of heated dies and shown in a conventional manner in Figures 6 and 8 as comprising a die block 13 having an arcuate recess 14 in one face and slidably mounted in a fixed support 15 and yieldingly urged to a predetermined position against a stop or abutment 16 arranged on the support 15 by a spring 17 compressed between an end portion of the support 15 and the die block 13 by having one end of the spring engaged by a pin 18 projecting from the end portion of the support and the opposite end engaged in a recess 19 in the rear face of the die block 13, as shown in Figure 8. The other die member comprises a plunger 20 having the forward face of arcuate

shape corresponding to the arcuate recess 14 and adapted to clamp the end of the holder 9 to the arcuate recess 14 and the forward movement of the plunger 20 moving the die block 13 against the force of the spring 17 and into engagement with a stop or abutment 21 on the support 15 whereby the adjacent end portions of the holder and tuft of hair are clamped together and the thermoplastic is forced into the material of the holder and the hairs of the tuft to retain the holder in clamped condition and secure the tuft of hair to the holder.

To adapt the thermoplastic to retain the holder in clamped condition and secure the tuft of hair to the holder, the dies 13 and 20 are heated by suitable means, and diagrammatically shown as being heated by electric resistance coils 22 mounted in the dies adjacent to the arcuate faces thereof. The engagement of the heated arcuate faces of the dies 13 and 20 will fuse the thermoplastic interposed between the tuft of hair and the holder and dissipate the alcohol vehicle, and the forward movement of the die plunger 20 and the resistance to said movement by the die block 13 will force the fused thermoplastic into the spaces between the hairs of the tuft and into the material of the holder.

After the thermoplastic has been thoroughly fused with the holder and the tuft of hair, the die plunger 20 is actuated from the die block 13 permitting the die block 13 to move under the force of the spring 17 and eject the formed brush from the support 15, and the brush dropping into a suitable depository, not shown, where the holder and thermoplastic will cool and the thermoplastic set in its formed condition.

The shape of the arcuate faces of the dies 13 and 20 will form opposite wall portions of the holder juxtaposed to the tuft of hair to extend in a slightly curved convex direction, as shown at 23, with the adjoining side portions of the holder extending substantially in the plane of the side wall of the body of the holder, as shown at 24 in Figure 7. This shape of the end portion of the holder causes the projecting portion of the tuft of hair to extend in flaring or diverging direction from the holder with the cross sectional shape of elliptical or flattened form, as shown at 25 in Figure 7.

To produce a brush having the bristles diverging from the holder with a circular cross section, the forming or clamping faces of the dies 13 and 20 are of an arc of approximately 180 degrees to form a complete circle when said faces are in mating relation with each other.

It is to be understood that the thermoplastic used in retaining the holder in clamped condition and securing the tuft of hair in the holder is not limited to the mixture of sulphur but may be any other thermoplastic having a comparatively low fusing temperature and the property of retaining its formed shape, such as "Bakelite" or condensite. The principal property of the thermoplastic is that the fusing or melting point thereof is below the scorching or burning point of the material of the holder.

Having thus described my invention, I claim:

1. A method of making brushes, consisting in providing a tube of fibrous material, a tuft of hair and a mixture of a thermoplastic and a vehicle therefor, the thermoplastic having a fusing point lower than the scorching temperature of the fibrous material of the tube and the vehicle having a boiling and evaporating point lower than the fusing temperature of the thermo-

plastic, applying the mixture of the thermoplastic and the vehicle to an end portion of the tuft of hair, inserting said end portion of the tuft of hair into one end of the tube with the opposite end portion of the tuft of hair projecting from the tube, and applying heat and pressure to said end of the tube to dissipate the vehicle and fuse the thermoplastic and unite the hairs of the tuft together and secure the tuft of hair in the tube by the fused thermoplastic being forced into the spaces between the hairs of the tuft and into the material of the tube.

2. A method of making brushes consisting in providing a tube of fibrous material, a tuft of hair and a mixture of a thermoplastic and a vehicle therefor, the thermoplastic having a fusing point lower than the scorching temperature of the fibrous material of the tube and the vehicle having a boiling and evaporating point lower than the fusing temperature of the thermoplastic, applying the mixture of the thermoplastic and vehicle to an end portion of the tuft of hair, inserting said end portion of the tuft of hair into one end of the tube with the opposite end portion of the tuft of hair projecting from the tube, and applying pressure and heat to the end portion of the tube having the tuft of hair engaged therein and form the projecting end portion of the tuft of hair to a desired shape and dissipate the vehicle and fuse the thermoplastic to adhesively secure the tuft of hair in the tube by the fused thermoplastic being forced into the spaces between the hairs of the tuft and into the material of the tube.

3. A method of making brushes, consisting in providing a tube of fibrous material and a tuft of hair, applying a mixture of sulphur and alcohol to an end portion of the tuft of hair, inserting said end portion of the tuft of hair into one end of the tube with the opposite end portion of the tuft of hair projecting from the tube, and applying heat and pressure to said end of the tube to dissipate the alcohol and fuse the sulphur and unite the hairs of the tuft together and secure the tuft of hair in the tube by the fused sulphur being forced into the spaces between the hairs of the tuft and into the fibrous material of the tube.

4. A method of making brushes consisting in providing a tube of fibrous material and a tuft of hair, applying a mixture of sulphur and alcohol to an end portion of the tuft of hair, inserting said end portion of the tuft of hair into one end of the tube with the opposite end portion of the tuft of hair projecting from the tube, and applying pressure and heat to the end portion of the tube having the tuft of hair engaged therein to form the projecting end portion of the tuft of hair to a desired shape and dissipate the alcohol and fuse the sulphur to adhesively secure the tuft of hair in the tube by the fused sulphur being forced into the spaces between the hairs of the tuft and into the fibrous material of the tube.
